UNITED STATES PATENT OFFICE

DANIEL B. RAYBURN, OF PENDLETON, INDIANA

SHACKLE FOR PRISONERS

Application filed March 13, 1931. Serial No. 522,346.

This invention relates generally to shackles for prisoners, and particularly to a shackle adapted to encircle the waist of a prisoner and which is provided with handcuffs to imprison in front of him, the hands and arms of the prisoner upon which the device is placed, to prevent the prisoner from having the use of his arms to inflict injury upon other persons or to unlock the waist encircling member.

It is an object of this invention to provide a new and novel shackle of the type alluded to, which is simple and effective, and which is easily carried upon the person of a warden or keeper, and which may be quickly and easily placed upon the person of a prisoner and removed therefrom, and which completely and effectively prevents the person from inflicting injury or escaping through the use of his hands and arms.

These and other objects of the invention, its nature, its composition and arrangement and combination of parts will be readily understood by anyone acquainted with the art to which this invention relates upon consulting the following description of the drawing, in which:—

Figure 1 is a general plan view of my improved shackle.

Figure 2 is a cross sectional view through the belt portion thereof.

Referring in detail to the drawing the numeral 5 generally designates the waist encircling portion, and the numerals 6 and 7 refer generally to hand cuffs of conventional type attached by means of swivels 8 and 9 which are connected to protuberances 10 and 11 formed on an enlarged, thickened portion 12 in the front portion of the waist encircling member 5. Commencing at the front points 13 and 14, arcuate portions 15 and 16 extend laterally and curve backwardly and at their rearward extremities 17 and 18 they are provided vertical hinges 19 and 20 which hingedly carry curved link portions 21 and 22. The rearward extremity of the link 22 carries a vertical hinge 23 of the same general formation as that of the hinges 19 and 20. To the hinge 23 is connected an arcuate toothed member 24 whose teeth 25 are adapted to be locked

in a sheath or lock casing 26 formed integral with and extending from the rearward extremity of the link 21. A key 27 is provided for operating suitable locking mechanism contained in the sheath 26. It will be obvious that the hinges 19 and 20 and 23 together with the longitudinally adjustable relationship of the sheath 26 and the member 24 provide for adjusting the size of the waist encircling member 5 to persons of different waist measure and the lock mechanism operating in connection with the teeth 25, provides for locking the belt to the required size.

I have in mind the provision of the belt made of chain or the like, to replace the portions 15 and 16 from the points 13 and 14 outwardly and rearwardly, as well as the portions 21 and 22. In the case of using chain or the like, the hinges 19, 20 and 23 will, of course, be unnecessary, the toothed member 24 being attached to the rearward end of one length of chain, and the sheath 26 being attached to the rearward end of the other length of chain. The construction of my improved shackle of chain or other flexible construction, provides that the whole device may be folded and collapsed so as to be of a suitable size for carrying in the pocket of a warden or keeper, so as to be constantly available at no inconvenience to the person carrying the same.

The swivels 8 and 9 are provided so as to give free movement and at the same time definite confining effect upon the hands and arms of a prisoner.

The sectional view of Figure 2 discloses generally the cross section of the belt 5 in the form illustrated in Figure 1, the belt sections 15, 16, 21 and 22 being formed of suitable hardened spring steel in the modification illustrated in Figures 1 and 2 and in the case that the shackle is constructed of flexible structure or of chain, a preferable form would be a double link case hardened chain having the general cross section illustrated in Figure 2.

It is to be definitely understood that I do not desire to limit the application of this invention to the particular modification set out herein to illustrate the principles thereof,

and any change or changes may be made in material, and in the structure and arrangement of the parts within the spirit of the invention and scope of the subjoined claims.

5. What is claimed is:—

1. A shackle for prisoners as described comprising a metallic waist belt having self locking girth adjusting means in its rear portion, a radially enlarged hand cuff mounting

10 at the center of its front portion, and a pair of spaced hand cuffs swivelly connected to said mounting and having self locking, girth adjusting means therein, said waist belt being made up of a plurality of hingedly connected sections.

15 2. A prisoner restraining device for application about the waist of the prisoner, comprising, a waist encircling member, comprising a rigid substantially semi-elliptical front member, an arcuate substantially quarter-elliptical locking member hinged to one end of the front member, an arcuate link hinged to the other end of the front member, and a locking tongue hinged to the free end

20 of the link and adapted to adjustably engage said locking member for enabling locking the waist encircling member so as to accommodate the girth of different prisoners, a pair of horizontally spaced individual hand- 25 cuff mountings located centrally of the front member, a swivel connection on each mounting carrying a handcuff.

30 3. A prisoner restraining device for application about the waist of the prisoner, comprising, a waist encircling member, comprising a rigid substantially semi-elliptical front member, an arcuate substantially quarter-elliptical locking member hinged to one end of the front member, an arcuate link hinged

35 to the other end of the front member, and a locking tongue hinged to the free end of the link and adapted to adjustably engage said locking member for enabling locking the waist encircling member so as to accommodate the girth of different prisoners, a pair of horizontally spaced individual handcuff mountings located centrally of the front member, a swivel connection on each mounting carrying a handcuff, said locking member, said link, and said locking tongue being rigid.

40 4. A prisoner restraining device for application about the waist of the prisoner, comprising, a waist encircling member, comprising a rigid substantially semi-elliptical front member, an arcuate substantially quarter-elliptical locking member hinged to one end of the front member, an arcuate link hinged to the other end of the front member, and a locking tongue hinged to the free end of the link and adapted to adjustably engage said locking member for enabling locking the waist encircling member so as to accommodate the girth of different prisoners, a pair of horizontally spaced individual handcuff

45 5. A prisoner restraining device for application about the waist of the prisoner, comprising, a waist encircling member, comprising a rigid substantially semi-elliptical front member, an arcuate substantially quarter-elliptical locking member hinged to one end of the front member, an arcuate link hinged to the other end of the front member, and a locking tongue hinged to the free end of the link and adapted to adjustably engage said locking member for enabling locking the waist encircling member so as to accommodate the girth of different prisoners, a pair of horizontally spaced individual handcuff

mountings located centrally of the front member, a swivel connection on each mounting carrying a handcuff, said locking member having at its free end a receptor, and said locking tongue having at its free end a rack adapted to be sheathed in and locked in the receptor so as to give the waist-encircling member the desired girth.

In testimony whereof I affix my signature.

DANIEL B. RAYBURN.
